Patented June 17, 1924.

Des. 64,921

UNITED STATES PATENT OFFICE.

FREDERICK L. MILLER, OF DETROIT, MICHIGAN, ASSIGNOR TO THE STUDEBAKER CORPORATION, OF SOUTH BEND, INDIANA, A CORPORATION OF NEW JERSEY.

DESIGN FOR AN AUTOMOBILE RADIATOR CAP.

Application filed March 27, 1924. Serial No. 9,084. Term of patent 14 years.

To all whom it may concern:

Be it known that I, FREDERICK L. MILLER, a citizen of the United States of America, and resident of Detroit, in the county of Wayne and State of Michigan, have invented a new, original, and ornamental Design for an Automobile Radiator Cap, of which the following is a specification, reference being had to the accompanying drawings, forming a part thereof.

In the drawings, Fig. 1 is a front elevation of an automobile radiator cap showing

my new design, Fig. 2 is a top view of the radiator cap shown in Fig. 1.

I claim:

The ornamental design for an automobile radiator cap as shown.

Signed by me at Detroit, Michigan, this 22 day of March, 1924.

FREDERICK L. MILLER.

Witnesses:

HODGSON S. PIERCE,
ELMER L. McINTYRE.
